CHAIR

Francis E. Leech, Glen, Md., assignor to Mueller
Furniture Company, Grand Rapids, Mich.

Application June 28, 1938, Serial No. 216,401

2 Claims. (CL 155—180)

This invention relates to upholstered chairs and more particularly to chairs having flat bowed springs for supporting the seat and back upholsteries.

5 An object of the invention is to provide a chair wherein the conventional tied coil spring and fixed upholstery are eliminated and to use in place thereof a plurality of flat resiliently supported springs in the seat and back and to upholster the chair with a readily removable padded unit.

10 A further object of the present construction resides in the novel and simple means provided for retaining the upholstery unit in position on the chair while allowing its instant removal for cleaning and for the purpose of dusting the cushions and under portion of the chair.

15 A still further object is the improved manner of retaining the flat seat springs in position on the chair frame and the combination of this retaining means with the means for securing the upholstery in snug fitted relation to the seat and back portions of the chair.

In the drawings.

20 Fig. 1 is a vertical cross sectional view showing the attachment of the upholstery to the chair frame;

Fig. 2 is an enlarged detail view in cross section of the front seat bar and spring structure;

25 Fig. 3 is an enlarged view partly in vertical cross section of the upper portion of the back of the chair showing one form of attachment of the upholstery;

Fig. 4 is a partial top plan view of the top of 30 the chair back illustrated in Fig. 3;

Fig. 5 is a modification of the upper portion of the back of the chair with an integral back covering flap attached to the upholstery;

Fig. 6 is an enlarged vertical cross sectional view of the middle portion of the chair, showing the point of jointure between the seat and back;

Fig. 7 is an enlarged plan view of the bottom of the chair taken on line 7—7 of Fig. 1.

In the drawings numeral 1 denotes the side rails of a chair seat, the spaced side rails being held together by front and rear transverse bars 2 and 3, respectively. While the side rails 1 and bars 2 and 3 may be supported by any suitable leg structure, it has been found convenient to use integrally combined front leg and arm members 4, whose ends are joined to integral rear leg and back members 5. A top transverse bar 10 joins the upper ends of the opposite leg and back members 5, while a second transverse reinforcing bar 11 secures the members 5 at a point

adjacent the jointure of the side rails 1 with the rear leg and back members 5.

The front and rear transverse bars 2 and 3 are positioned within the chair frames, as illustrated in detail Figs. 2 and 6, where it will be seen 5 that the front bar 2 has a curved upper edge and is retained between the side rails 1 in a substantially vertical plane. The rear bar 3, on the other hand, has a curved tapered top and rearward side surface and is set on an oblique angle. 10 A plurality of parallel spaced substantially flat seat supporting spring straps 16 are secured between the front and rear bars 2 and 3, the ends of the straps being hinged or riveted to downwardly curved end members 16, which coincide 15 with the outer sides of the bars 2 and 3 and are retained in position thereagainst by a fastening means to be hereinafter described.

Both the series of front and rear curved end hangers 16 are reinforced by comparatively stiff 20 spring checks or plates 17, which contact directly on the front and rear bars, with the hangers 16 overlapping and extending beyond the upper curved ends of the plates 17.

The lower ends of the front series hangers 25 16 and spring plates 17 are rigidly attached to front bar 2 by an outer wooden or metal strip 20 provided with an inner cut-away section 21 to accommodate the thickness of the hangers and plates. Screws 22 are inserted through strip 30 20 and registering openings 23 in the sets of hangers and plates and extend into the front bar 2. A fabric or other flexible strip 25 is placed between the lower abutting portions of the strip 20 and bar 2 and extends slightly below the bottom of the bar, with one half of a Zipper type 35 separable fastener 26 secured thereto.

The series of hangers 16 and stiffening plates 17 may be similarly attached to the rear bar 3, although it is preferable to extend the lower 40 ends of the hangers and plates downwardly and around the bottom edge of the bar. Here a metal or wooden strip 27, provided with screws 28, passes through the hangers and plates, and retains the elements in secure position against 45 bar 3. A flexible strip 29, having one half of a zipper type separable fastener 30 on its outer edge, is provided between the strip and bar, see Fig. 5.

The transverse middle reinforcing bar or brace 50 11 is formed of two sections 31 and 32 joined by screws 33 and retains therebetween a flexible strip 34 having one half of a Zipper type separable fastener 35 thereon.

The upholstery covering of the seat and back 55

portions is preferably made as a unit, the padded seat portion 40 being connected by an unpadded section or web 41 to the padded back portion 42. As shown in Figs. 1, 6, and 7, a strip 43, having one half of a Zipper type fastener 44 thereon, is sewed or otherwise secured to the underside of the web 41 and cooperates with Zipper half 35 to hold the mid section of the upholstery to the rear portion of the chair frame.

10 The lower front edge 45 of the seat pad or cushion 40 may have a fiber or metal strip 46 in the bottom thereof with a flexible strip 47 sewed or otherwise secured to the under surface thereof, terminating in one half of a Zipper type separable fastener 48, which cooperates with Zipper half 26 to hold the lower edge 45 snugly against the front bar 2.

15 The back pad or cushion 42 rests on a series of spaced parallel flat bowed transverse springs 50 fastened to the upper portions of the back members 5; the ends of the springs being loosely covered by flexible side pieces 51 so that they are hidden from view, if the back cushion is not tight against the frame.

20 Figs. 3 and 5 disclose alternative methods of securing the top outer edge 52 of the back cushion, although in either form a fiber or metal strip 53 is sewed or otherwise secured in the edge 52 which cooperates with and is retained in groove 54 formed between the main back brace 10 and auxiliary strip 55. In the construction illustrated in Fig. 3, one half of a Zipper type separable fastener 56 on strip 57 is affixed to the back brace 10 within top groove 54 and cooperates with a similar fastener 58 sewed to strip 59 fastened adjacent the upper edge of the back cushion. The top strip 53 when inserted in groove 54 positions the back cushion against the back bar 10, while the separable fastener prevents the top strip and back cushion from displacement.

25 The back of the chair frame is covered with an ornamented sheet 65, which may have a surface of cloth matching the upholstery cover.

30 As shown in the modification in Fig. 5, the top Zipper fastener 57-58 is dispensed with and in lieu thereof an outer back panel 60 is attached to the upper edge of the back cushion. This

35 panel 60 is preferably of similar material to the upholstery covering so that it finishes off the back of the chair in a pleasing manner. The lower end of the panel 60 is provided with one half of a Zipper type fastener 61 secured to strip 52 and cooperates with a similar fastener 63 secured to strip 64 retained between the bottom of rear bar 3 and fastening strip 21.

40 What I claim is:

1. In a chair or the like, means securing an 10 upholstered pad to the frame of a spring structure in which flat spring strips span opposite sides of said frame and have their ends secured to the rails of said frame by cover cleats overlying the ends of said spring strips and secured to 15 said rails, said securing means comprising a strip of fabric material having an edge lying between said cleat and said frame and secured therein, separable fasteners secured between and extending beyond the edges of the front and rear rails 20 of the seat frame and the said auxiliary strips, and similar separable fasteners secured to the lower edge of the covering and to the end of the said back extension for cooperation therewith.

2. In a chair or the like, means securing an 25 upholstered cushion to the frame of a spring structure in which flat spring strips span opposite sides of said frame and have their ends secured to the rails of said frame by cover cleats overlying the ends of said spring strips and secured to 30 said rails, said securing means comprising a strip of fabric material having an edge lying between said cleat and said frame and secured therein and having a portion of a separable fastener thereon secured to the bottom rail of the back frame and 35 a unitary upholstery pad comprising seat and back cushions joined by a transverse web portion adapted to be positioned over the seat and back springs, an unpadded panel secured to the top edge of the back cushion, and adapted to 40 overlie the rear surface of said back frame, a portion of a separable fastener secured to the underside of said web portion and also to the end of said panel, said fasteners cooperating with one another to secure the upholstery at the several points to said chair.

45 FRANCIS B. LEECH.
